UNITED STATES PATENT OFFICE.

OTTO MALCHER, OF CHICAGO, ILLINOIS, ASSIGNOR TO CASPAR STAUB, JR., OF CHICAGO, ILLINOIS.

CHECK PROTECTOR.

Application filed November 21, 1921. Serial No. 516,715.

To all whom it may concern:

Be it known that I, OTTO MALCHER, a citizen of the United States, residing at Chicago, in the county of Cook and State of Illinois, have invented certain new and useful Improvements in Check Protectors, of which the following is a specification.

This invention relates to machines for protecting checks and other documents from alterations, and has for its object the provision of a machine of the class named which shall be of improved construction, efficient and convenient to operate and simple and economical in manufacture.

15 The invention is exemplified in the combination and arrangement of parts shown in the accompanying drawings and described in the following specification and it is more particularly pointed out in the appended 20 claims.

In the drawings,

Fig. 1 is a vertical sectional view through a check protector, showing one embodiment of the present invention.

25 Fig. 2 is a view similar to Fig. 1, with the parts in a different position from that of Fig. 1.

Fig. 3 is a top plan view of the check protector with parts omitted.

30 Fig. 4 is a front elevation of the carriage mechanism.

Fig. 5 is a detail showing the escapement mechanism of the carriage.

35 Fig. 6 is a fragmentary section on line 6—6 of Fig. 3.

The present invention provides a check protector in which a check is inserted in a frame in which the face of the check is visible and which is provided with a spring 40 clamp which serrates the paper upon which the payee's name is written. The amount of the check is cut into the paper and at the same time the fibers where the paper is partially cut are saturated with ink, making 45 erasure impossible without destroying the document. The impression of the amount upon the check is produced by simply striking the different number in a keyboard corresponding to the figures of the amount of 50 the check. The keyboard is also provided with any necessary words such as "Pay," "Dol." and "Cts."

The device comprises a sheet metal casing 10 mounted on a base 11, and having a trans- 55 verse stationary shaft 12, upon which key

levers 13 are mounted in spaced relation to one another for pivotal movement about the shaft. Each key lever is provided with a downwardly extending arm 14, having a contact foot 15. Springs 16 are attached to the arms 14 and retain the key levers 13 in their uppermost position against a fixed shaft 17 extending transversely of the frame 10. Pivoted on the shaft 12 is a pair of arms 18, which support a universal 60 bar 19 disposed in the path of the contact feet 15 on the key levers. It will be seen from Fig. 1 that the feet 15 are of different lengths so as to permit different amounts of movement of the key levers prior to engagement of the feet with the universal bar 19. The amount of such preliminary movement is proportional to the numbers which the different keys represent.

Pivoted on a shaft 20 which 75 extends transversely of the machine and is supported by the side walls of the frame 10, is a frame 21 having side walls 22 and 23. A spring 24 is attached to an extension 25 formed on the side wall 22 for retaining the 80 frame 21 in its forward position against the shaft 17, as shown in Fig. 1. Pivoted on the shaft 20 adjacent the inner face of the side wall 22 is an upright bar 26, having a rack segment 27 at its upper end. 85 The segment 27 meshes with a pinion 28 pivoted at 29 on the side plate 22 of the frame 21. Fixed to the pinion 28 is a gear 30, which meshes with a pinion 31, rigidly fixed to a type wheel 32 journaled on a 90 shaft 33 carried by a lateral extension 34 on the side plate 22. The type wheel 32 carries on its periphery the various characters 35 which are used in stamping the check or other document. When the segment 27 95 is moved forwardly relative to the frame 21, the type wheel 32 will be rotated upon its pivot through the chain of gearing described to bring the different characters into printing line. The bar 26, which carries the segment 27, is provided near the pivot 29 with a gear segment 36, which meshes with teeth 37 on the end of an arm 38, pivotally mounted on the shaft 12. Extending through the arm 38 is an upper 105 universal rod or bar 39, which is supported at its ends by arms 40, also pivoted on the shaft 12. The universal rod 39 is held in its uppermost position by springs 41 secured to the side walls of the frame 10 and to the 110

opposite ends of the rod 39. The rod engages the lower edges of the various key levers 13, so that whenever a key is depressed the rod 39 will move downwardly carrying with it the arm 38 and thus rotating the bar 26 about the shaft 20 to drive the gear wheels secured to the type wheel 32. The amount of rotation of the type wheel will depend upon the distance the key lever moves before its contact foot 15 engages the lower universal bar 19. This engagement will release the frame 21 and move the frame and type wheel in unison with one another to bring the character which has been rotated into printing line against the paper in the carriage frame.

During the movement of the key lever to set the type wheel the frame 21 is held in fixed position by a detent 42 pivoted on the shaft 12 and having its forward end in contact with a lug 43 bent laterally from the side plate 22 of the frame 21. The detent 42 is provided with a downwardly extending arm 44 having an opening 45 therein surrounding a transversely extending shaft 46, the opening being larger than the shaft, as shown in Fig. 1, to permit a limited lost motion of the arm relative to the shaft. A spring 47 is connected to lugs 48 and 49 on the arm and shaft respectively, to resiliently hold the parts in the position relative to one another shown in Fig. 1. The lower end of the arm 44 is fixed to the universal bar 19 and the shaft 46 is carried by arms 50 pivoted on the shaft 12. When a foot piece 15 strikes the universal bar 19 it will move the arm 44 relative to the shaft 46 until the opposite side of the opening 45 engages the shaft. This preliminary movement of the arm 44 relative to the shaft 46 will disengage the detent 42 from the lug 43, thus freeing the frame 21 to move rearwardly for bringing the type wheel against the paper. As shown in Figs. 3 and 6, a curved arm 51 is pivoted on the shaft 12 and has its lower end fixed to the shaft 46. The opposite end of the arm 51 is provided with a gear segment 52, which meshes with a segment 53 formed integrally with the side wall 23 of the frame 21. After the frame 21 has been released from the detent 42, further movement of the arm 44 will carry the shaft 46 to the right as viewed in Fig. 1, and rotate the frame 21 to swing the type wheel against the paper. During the movement of the frame 21 upon its pivotal support the type wheel will be held in fixed position on the frame for the reason that the arms 38 and 52 will move in unison with one another about the shaft 12 and will be retained in fixed relation by the foot piece 15, which engages the universal bar 19. This relation will depend upon the length of the foot piece of the particular key depressed and will, of course, determine which

character will strike the paper. The relation of the parts at the time the impression is made by the printing wheel is shown in Fig. 2.

The characters 35 are inked by a roller 54 supported by arms 55 and 56, pivotally mounted on the shaft 33 of the printing wheel 32. The arm 56 has a gear segment 57 formed integral therewith, the teeth of which mesh with a pinion 58 journaled at 59 on the side plate 23 of the frame 21. The pinion 58 also meshes with a gear segment 60 carried on a fixed upright 61. As the frame 21 is moved rearwardly during the printing operation the pinion 58 will travel on segment 60 and rotate the segment 57 to raise the roller 54 and cause it to travel over the face of the type 35, thus inking the type. The roller 54 is journaled in slots 62 and resiliently held against the face of the type by springs 63. Ink may be supplied to the periphery of the roller from time to time as required by the use of the machine. The rotation of the arms 55 and 56 upon their pivotal supports 33 will raise the roller above the printing line at each printing operation so that it will not interfere with the type wheel, and the same movement will cause the roller to traverse the type which is moved to printing position for each particular printing operation.

The carriage for supporting the paper comprises a plate 64 having rearwardly bent side edges 65 slidably mounted on guide rods 66. The guide rods 66 are mounted on a bracket 67 carried by rods 68 extending transversely of the frame 10 adjacent the rear portion thereof. A serrated backing block or platen 69 is secured to the bracket 67 by screws 70 in position to project through an opening 71 in the plate 65. The serrated face of the block 69 is in approximate alignment with the front face of the plate 64, so that the serrations engage the back of the sheet of paper held against the plate. The characters 35 on the periphery of the type wheel 32 are provided with peripherally extending grooves in position to mesh with the serrations in the block 69. In this way, whatever character strikes the paper the serrations of the type and the block 69 will intermesh with one another and correspondingly serrate the paper and at the same time impregnate the fibers with the ink on the type. The opening 71 in the plate 65 is made of sufficient length to provide for the necessary movement of the carriage for writing the amount to be impressed upon the paper, together with any other words or characters desired.

A supporting bracket or ledge 72 is formed on a plate 73, having rearwardly bent lugs 74 at the opposite ends thereof, which enter slots 75 in the plate 65. The plate 73 is provided with a slot 76, which

receives a screw 77 fixed to the plate 65 and provided with a thumb nut 78, by which the support or ledge 72 may be held at different heights for adjusting the various 5 checks to their proper position in the carriage. A pair of arms 79 are pivoted on a rod 80 carried by the bent-over edges 65 of the plate 64. Coiled springs 81 press the arms 75 toward the plate 64 to bear upon 10 the paper supported by the carriage and hold the paper in place. A cross-bar 82 connects the arms 79, the rear face of the bar being serrated to intermesh with teeth on a corresponding bar 83 supported by the 15 plate 64 and flush with the front edge thereof. When the check or other paper shown in broken lines at 85 in the drawing is inserted in the carriage the arms 79 are first drawn forwardly and the check dropped 20 into place between the arms and the plate 64. The arms are then released and are moved backwardly against the plate by the springs 81 with sufficient force to cause the teeth on the plate 82 to partially mutilate 25 the paper against the bar 83. These teeth are so placed that they will strike the name of the payee upon the check, thus preventing erasures or alteration of the name of the payee.

30 The carriage or supporting plate 64 is drawn to the left by a spring 90, and its movement under the influence of the spring is controlled by escapement mechanism shown in Fig. 5. A rack 91 is secured to 35 the carriage frame by screws 92, as shown in Figs. 1, 2 and 4, and a pair of escapement dogs 93 and 94 are pivoted at 95 on an ear 96 secured to one side plate of the bracket 67. The dog 94 is provided with a 40 lever arm 97 having a spring 98 secured thereto and attached to a pin 99 on the bracket 67. The spring 98 retains the dog 94 against a limit stop 100 on the bracket 67. The dog 94 projects beyond its pivot 45 95 and carries a lug 101 for engaging the dog 93. The projecting portion of the dog 94 also carries an ear 102, having a spring 103 secured thereto. The opposite end of the spring 103 is attached to an ear 104 on 50 the dog 93. This spring resiliently holds the dog 93 against the stop 101. An actuator arm 105 for the escapement mechanism is pivoted on the shaft 12 and has a downwardly and rearwardly projecting arm 106 55 attached to the shaft 46. When the shaft 46 is moved upwardly by one of the key levers, the arm 105 will press the dog 94 in front of one of the teeth on the ratchet bar 91 and thereafter release the dog 93 from the tooth of the bar with which it is in engagement. The dog 94 will hold the ratchet bar 91 and the carriage in fixed position during the printing operation. When this 60 dog is released by the return movement of the arm 105, the spring 98 will withdraw

the dog 94 from contact with the ratchet tooth and at the same time swing the dog 93 into position to engage the next tooth on the ratchet. In this way the carriage is fed one letter space between the printing operations. Any other suitable escapement mechanism can, of course, be used for this purpose.

I claim:

1. The combination with a type wheel, 75 of a frame mounted for rotation about the axis of said wheel, an inking roller carried by said frame in position to engage the periphery of said wheel, a stationary rack, and gearing connected with said rack and 80 frame for rotating said frame about its axis to cause said inking roller to traverse the periphery of said wheel when the axis of said wheel is shifted relative to said rack.

2. A check protector comprising a frame 85 for supporting a check, a clamping member for retaining said check in said frame, and a toothed device carried by said clamping member for engaging said check and partially mutilating the material thereof to prevent alterations of entries on said check.

3. A document protector comprising a sheet holding frame, a spring clamp for retaining a sheet in said frame, and a toothed member 95 on said clamp for engaging said sheet to form indentures therein.

4. A document protector comprising a sheet supporting frame, a toothed member for engaging a sheet in said frame, and a clamp for holding a sheet in said frame, 100 said clamp having teeth thereon for cooperating with the teeth on said member to form indentures in said sheet.

5. A document protector comprising a sheet supporting frame, a serrated block 105 having the teeth thereof arranged substantially flush with the face of said frame, a spring clamp for retaining a sheet in said frame, and a serrated member carried by said clamp and arranged to cooperate with the serrated member on said frame to form indentures in said sheet for the prevention of alterations therein.

6. A document protector comprising a sheet holding frame, a toothed clamp for 115 retaining a sheet in said frame and for forming indentures in a portion of said sheet having an entry thereon, and toothed type for forming indentures on other portions of said sheet.

7. A document protector comprising a movable frame, a toothed member carrier by said frame and movable therewith for forming indentures on one portion of the sheet carried by said frame, a stationary toothed member, and toothed type arranged to cooperate with said stationary member to form indentures on other portions of said sheet.

8. A document protector comprising a mov- 130

- able frame for supporting a sheet, a spring clamp for retaining a sheet in said frame, said clamp having a toothed member thereon for engaging a portion of said sheet to form indentures therein, a stationary toothed member for engaging said sheet, means for shifting said frame to bring different portions of said sheet into juxtaposition with said stationary member, and separately operable toothed type for cooperating with said stationary member to form indentures in said sheet and thus impress the characters of said type therein.
9. A document protector comprising a movable carriage, a spring clamp for retaining a sheet in said carriage, a toothed member carried by said clamp for forming indentures in a sheet on said carriage, a stationary toothed member for forming indentures in a sheet on said carriage, type for cooperating with said stationary member, and an adjustable stop for positioning a sheet on said carriage relative to said toothed members.
10. A document protector comprising a rotary wheel having characters on the periphery thereof, a pivoted frame for supporting said wheel, an arm movable relative to said frame to rotate said wheel to bring different characters thereon into printing line, a detent for holding said frame against movement during operation of said arm, keys for moving said arm different amounts to bring the character corresponding to the particular key depressed into printing line, means actuated by said keys for releasing said detent after the movement of said arm, and means operated by the further movement of a key to shift the arm and frame bodily to produce an impression of a character on said wheel.
11. A document protector comprising a rotary type wheel, a frame for supporting said wheel, an arm movable relatively to said frame for rotating said wheel, a universal member for moving said arm to rotate said wheel during the first portion of the movement of any key, a detent for said frame, mechanism for releasing said detent and shifting said frame and arm bodily, and means connected with each of said keys for actuating said last named mechanism after said arm has been moved amounts varying for the different keys.
12. A document protector comprising a rotary wheel a universal member for rotating said wheel, a plurality of keys for actuating said universal member during the first portion of the movement of any key, mechanism for shifting said wheel bodily to form an impression of a type thereon, a detent for retaining said shifting means in fixed position, a universal member for actuating said shifting means, a lost motion connection between said detent and said universal member, and means actuated by said keys for first releasing said detent and subsequently operating said universal member to actuate said shifting means.

In testimony whereof I have signed my name to this specification on this 18th day of November, A. D. 1921.

OTTO MALCHER.
